MULTIPLE REFLECTOR FOR LIGHTING UNITS

Eric B. Hallman, Conshohocken, and Charles C. Weaver and Charles A. McGough, Jr., Philadelphia, Pa., assignors to Electric Service Supplies Company, Philadelphia, Pa., a corporation of Pennsylvania

Application October 22, 1941, Serial No. 416,030

3 Claims. (Cl. 240—7.35)

This invention relates to lighting fixtures and more particularly to improvements in the design and construction of reflectors such as are employed in vehicle interior lighting fixtures.

Among the principal objects of the present invention is to provide a vehicle lighting fixture with a single reflector of such character as will produce, from a single source of light, a plurality of directionally controlled beams of light, each of sufficient intensity to insure adequate illumination at and throughout the several reading zones respectively illuminated by the said beams of light.

Heretofore and prior to the present invention, vehicle interior lighting has involved either the use of a plurality of separate lighting units spaced in the vehicle to provide for general illumination without regard to the individual spacing of the passenger seats, or the use of separate lighting units designed to spot light two or more adjacent reading zones. Throughout this specification and in the claims appended hereto, the term "adjacent reading zones" is employed to mean the reading planes of a pair of laterally disposed or side-by-side seats of a two-passenger cross-seat; the reading planes of a pair of successive aisle or window seats arranged in tandem, i. e., longitudinally of the vehicle; or the reading planes of a pair of seats laterally and longitudinally spaced from each other to the extent of a single seat, the reading planes in this last instance being spaced from each other in a direction extending diagonally of the longitudinal axis of the vehicle.

The present invention contemplates not only the use of a lighting unit having a single source of light to illuminate a pair of adjacent reading zones, but also the provision of special reflector means in such lighting unit to project separate and independent beams of light emanating from such single light source to adequately illuminate each of the adjacent reading zones.

More specifically it is an object of the present invention to provide in a single lighting unit a composite reflector made up of a plurality of parabolic reflector sections having the same or different focal lengths, said reflector sections being so related that their focal points are brought into substantial coincidence, in consequence of which the composite reflector projects, from a single source of light located at the common focal point of the several reflector sections, separate beams of light, the axes of which are angularly related to each other. Thus, the composite reflector of the present invention provides

for the projection of a plurality of independent, directionally controlled beams of light emanating from a single source for illuminating two or more adjacent reading zones.

Other objects and advantages of the present invention will appear more fully hereinafter, it being understood that the present invention consists in the combination, construction, location and relative arrangement of parts, all as will be described in detail hereinafter, as shown in the accompanying drawings and as finally pointed out in the appended claims.

In the accompanying drawings, which illustrate several different embodiments of the present invention.

Figure 1 is a plan view of the interior of a passenger vehicle showing various typical seating arrangements each involving two or more separate reading zones which may be illuminated by single lighting fixtures of the present invention;

Figure 2 is a plan view of a reflector unit constructed in accordance with the principles of the present invention for projecting three separate beams of light from a single light source;

Figures 3 and 4 are sectional views taken on the lines 3—3 and 4—4 of Figure 2;

Figures 5 and 6 are diagrammatic views illustrating the principles involved in the construction of the reflector of Figure 2;

Figure 7 is a plan view of a two-beam reflector unit;

Figures 8 and 9 are sectional views taken on the lines 8—8 and 9—9 of Figure 7;

Figures 10 and 11 are diagrammatic views in illustration of Figure 7;

Figure 12 is a plan view of a modified form of two-beam reflector unit;

Figures 13 and 14 are sectional views taken on the lines 13—13 and 14—14 of Figure 12;

Figures 15 and 16 are diagrammatic views illustrative of the reflector unit of Figure 12;

Figure 17 is a plan view of a four-beam reflector unit;

Figures 18 and 19 are sectional views taken on the lines 18—18 and 19—19 of Figure 17;

Figures 20 and 21 are sectional views taken on the lines 20—20 and 21—21 of Figure 17; and

Figures 22, 23, 24 and 25 are diagrammatic views illustrative of the reflector unit of Figure 17.

Referring now to the drawings and more particularly to Figure 1 thereof which illustrates a typical seating arrangement in an automotive passenger vehicle, it will be observed that this seating arrangement includes at least four dif-

ferent groupings of passenger seats, each of which groupings is adapted to be illuminated by a single lighting fixture of the present invention. Thus, seat grouping A includes a longitudinal seat for two passengers having adjacent reading zones disposed side by side, while seat grouping B includes a cross-seat for two passengers having a pair of side by side adjacent reading zones. Seat grouping C includes a longitudinal seat for three passengers having three adjoining reading zones, and seat grouping D includes a pair of cross-seats arranged in tandem to provide a seating arrangement for four passengers, each passenger seat having, of course, a separate reading zone. In each seat grouping, the approximate position of the overhead single lighting unit as employed and constructed in accordance with the principles of the present invention is designated by the reference character x , it being further noted that while in the case of each of the seat groupings A and C the lighting unit is located almost directly above the center of the seating zones to be illuminated, in the case of the seat grouping B the lighting unit is located somewhat off-center as respects the seating zones of said grouping. In the case of the four passenger seat groupings D the lighting unit is located centrally of the four reading zones.

The lighting unit employed for illuminating the seat grouping A is shown in Figures 12 to 14, that of seat grouping B is shown in Figures 7 to 9, that of seat grouping C is shown in Figures 2 to 4, and that of seat grouping D is shown in Figures 17 to 21.

Considering first the lighting unit for the simplest multiple seating arrangement as represented by the seat grouping A in Figure 1, reference is had to Figures 12 to 14 wherein the reflector unit of the present invention includes, as shown, a reflector 10 in the form of a sheet metal stamping having a central concaved portion 11 bounded by a flat marginal rim 12. The sections of the concaved reflecting portion 11 of the reflector taken in the transverse planes of lines 13-13 and 14-14 of Figure 12 are different, as clearly appears from a comparison of the transverse sections shown in Figures 13 and 14. However, each of these latter sections is symmetrical with reference to the central or focal axis of the reflector, for a purpose which will be apparent hereinafter.

It will be observed that whereas in its transverse section of Figure 14 the shape of the reflector 11 is that of a simple parabola having a predetermined focal length and fixed focal point 13, in its transverse section of Figure 13 the reflector shape has been changed from this simple parabolic contour and instead is composed of a pair of similar parabolic sections 13^a and 13^b, the focal axes of each of which has been swung about the common focal point 13 to provide the reflector with a peak or ridge 14 extending transversely thereof along the line 14-14 of Figure 12.

Figures 15 and 16 illustrate diagrammatically the principles involved in obtaining the reflector 11 having the transverse section shown in Figure 13.

Referring now to Figures 15 and 16, it will be observed that the parabolic section 13^a of the reflector 11 is derived by severing the simple parabolic section p along the transverse plane of the line $f-d$ to provide a parabolic section $a-d$ which is swung about the transverse axis of the focal point f through a predetermined angle (e. g.—12°) so as to present the point d at the focal axis of the simple parabola p . Similarly, the

parabolic section 13^b of the reflector 11 is derived by severing the simple parabolic section p along the transverse plane of the line $f-b$ to provide a parabolic section $b-e$ which is swung in opposite direction about its focal point through a corresponding angle (e. g.—12°) so as to present the point b at the focal axis of the simple parabola. There is thus obtained the composite parabolic form shown in Figure 16 wherein the parabola section $a-d$ and the parabola section $b-e$ are so related that their respective focal axes $c-f$ and $c'-f$ intersect one another at the focal point f of the simple parabola p . When two such parabolic sections have been obtained, they are joined together in the relation just described and their free edges are trimmed and out-turned to provide a radially extending supporting rim 12. In actual manufacture, of course, the parabolic sections so joined together are employed as a form in the production of suitable dies from which reflectors of the character shown in Figures 12 to 14 may be stamped out uniformly and in quantities as desired.

The reflector 11 so formed is then provided with a suitable lamp socket 14^a for receiving a lamp 15, the source of light of which is disposed substantially at the focal point of the reflector. As most clearly appears in Figure 16, the reflector 11, by reason of its pair of reflecting sections 13^a and 13^b each of parabolic form, projects a pair of intersecting light beams from the single source of light, the rays of one light beam paralleling the focal axis $c-f$ of the reflector section $a-d$ and those of the other light beam paralleling the focal axis of the reflector section $b-e$.

The reflector 11 is, of course, mounted in a suitable housing therefor (not shown), as, for example, in a lens-equipped casing of the type shown in United States Letters Patent No. 2,249,357, granted July 15, 1941, to Herbert J. Graham, to thereby complete the lighting unit, and when such unit is employed to illuminate a seat grouping such as that designated A in Figure 1, the two beams projected from the unit respectively illuminate the two reading zones of the seat grouping A. Obviously, by varying the angle of rotation of the reflector sections $a-d$ and $b-e$ about the transverse axis of the focal point f , the angular relation of the projected beams may be changed as desired. It will be apparent that in order to secure proper and adequate illumination of the reading zones of seat grouping A (see Figure 1), it is necessary to vary the angular relation of the projected beams to compensate for variations in the height of the lighting fixture above said reading zones. Inasmuch as the lighting fixtures in passenger vehicles are usually mounted upon the ceiling, the height of the fixture above the reading planes is fixed and the angular relation of the projected beams is accordingly predetermined to insure projection of the crossed beams respectively upon the reading zones to be illuminated.

It will be noted in connection with the lighting fixture of Figures 12 to 14 that it is designed to project the beams downwardly in such manner that their central axes are disposed substantially in the transverse plane of the fixture intersecting the line 13-13 of Figure 12. In other words, there is no deviation of the projected beams frontally or rearwardly of the seat A, this being due to the fact that the reflector is symmetrical with reference to its focal point 13 in its transverse section taken on the line 14-14 of Figure 12. In the seat grouping A such lateral deviation

or directional adjustment of the projected beams is unnecessary because the lighting unit is mounted directly above the center of the zones to be illuminated.

However, in the case of seat grouping B, it will be noted that the lighting unit is disposed above the back of the cross-seat, i. e., somewhat to the rear of the center of the reading zones to be illuminated. In such case, a lighting fixture is employed having the reflector unit of Figures 7 to 9. This latter unit is constructed similarly to that of Figures 12 to 14 in that it also is provided with a central concaved reflector part 16 which is composed of a pair of identical parabolic reflector sections 17^a and 17^b which are derived from simple parabolic shapes and merged in the transverse plane of reflector extending along the line 8-8 of Figure 12, the focal points of these reflector sections 17^a and 17^b being coincident, as at 18. The beams of light respectively projected from these sections 17^a and 17^b are shown in Figure 11 wherein it will be noted that they are angularly related to the extent predetermined by the angles through which said sections are swung about the transverse axis of the focal point (e. g.—10°).

In order to impart a directional characteristic to the angularly related beams respectively projected from the parabolic sections 17^a and 17^b of the reflector, the latter as a whole is rotated through a predetermined angle (e. g.—22°) about the axis of the focal point 18 extending transversely of the line 8-8 of Figure 7. The focal axis of the parabolic line of emergence of the sections 17^a and 17^b is thus angularly related to the vertical (see Figure 8), in consequence of which the two beams respectively projected by the reflector sections 17^a and 17^b not only intersect one another below the focal point 18 of the reflector, but also are disposed with their central axes disposed commonly in a plane inclined with respect to the vertical. Thus, when the lighting unit as designed for application to the seat grouping B of Figure 1 is mounted above and somewhat to the rear of the reading zones, the two beams projected therefrom will be forwardly directed and will intersect one another to respectively illuminate the two reading zones arranged in side by side relation.

The reflector unit constructed in accordance with the principles of the present invention and designed for application to a seat grouping C, which includes three adjoining seats and a corresponding number of reading zones arranged in side by side relation, is shown in Figures 2 to 4, inclusive. Referring now more particularly to these latter figures, it will be observed that the reflector 18^a is provided with a central concaved reflecting part 19 and a flat marginal supporting rim 20. The central concaved reflecting part 19 of the reflector is composed of three separate parabolic sections 20^a, 20^b and 20^c. The parabolic sections 20^a and 20^b are counterparts of one another and are laterally spaced apart to embrace therebetween the intermediate reflecting section 20^c, the meeting edges of the several parabolic sections of the reflector being smoothly merged together along the lines 21 and 22, as appears most clearly in Figures 2 and 3.

As in the reflector units previously described, the several parabolic sections 20^a, 20^b and 20^c of the reflector unit 18 are all relatively so related as to present their respective focal points in substantial coincidence, this in spite of the fact that the intermediate parabolic section 20^c is of a dif-

ferent order from and has a different focal length than that of the parabolic sections 20^a and 20^b. The reflector 18^a is provided with a lamp socket 23 for receiving a lamp 24, the lamp and socket being operatively so associated with the reflector as to present the lamp filament or source of light at the common focal point 25 of the reflector.

Figures 5 and 6 illustrate the principles involved in the construction of the reflector unit of Figures 2 to 4. As shown in these Figures 5 and 6, the laterally spaced reflector sections 20^a and 20^b are obtained by splitting a simple parabolic reflector *p*, as shown in Figure 5, along the transverse plane of the focal axis *c-f*. The two halves of the parabolic reflector are then oppositely rotated about a transverse axis extending through the focal point *f* through predetermined angles (e. g.—23°). Thereupon a separate parabolic section is fitted between the proximate edges of the separated reflector sections, the intermediate reflector section selected for this purpose being of parabolic form and of such focal length that its focal point coincides with the common focal point of the separated reflector sections. In the particular illustration shown in Figures 2 to 6, the reflector sections 20^a and 20^b are each of $\frac{1}{2}$ inch focal length, while the intermediate parabolic sections is of $\frac{1}{8}$ inch focal length, it having been found that parabolic sections of such focal lengths may be smoothly related to form a multiple reflector unit having a common focal point as shown.

It will be understood, of course, that in the case of the reflector unit shown in Figures 2 to 3, as in the case of all of the reflector units described in this specification, the several parabolic sections which go to make up the complete unit are initially assembled to provide a form from which suitable dies are made, these dies being then employed to press the reflector units out of sheet metal. Of course, any method may be employed in the formation of the multiple reflector units herein shown and described.

The reflector unit of Figures 2 to 4 provides for the projection of three separate beams of light, the beams emanating from the reflector sections 20^a and 20^b being angularly related so as to cross one another below the focal point of the reflector for illuminating the reading zones of the outermost seats of the seat grouping C. The intermediate reflector section 20^c projects a third beam downwardly through the focal point of the reflector to illuminate the reading zone of the central seat of said grouping. As in the case of the lighting unit of Figures 12 to 14 for use in illuminating the seat grouping A, the three beams projected by the reflector unit of Figures 2 to 4 do not deviate frontally or rearwardly of the seat C. Instead, all of the beams are disposed so that their central axes lie substantially in a vertical plane extending through the common longitudinal center line of the seats C. Of course, if it is desired to impart a directional characteristic to the beams of light respectively projected from the several reflector sections of the reflector unit, all that would be necessary in such case would be to rotate the unit as a whole through a predetermined angle about a horizontal axis extending transversely along the line 3-3 of Figure 2 and through the focal point 25 of the reflector unit. In other words, a directional characteristic may be imparted to the three beams of the reflector unit in the same manner as such directional characteristic was

imparted to the two-beam reflector unit of Figures 7 to 9.

Finally, for application to a seat grouping such as D shown in Figure 1, which includes as many as four separate reading zones, the reflector unit of Figures 17 to 20 may be employed. This latter unit consists of a central concaved reflecting part 26 having a flat marginal rim 27, the central concaved part 26 being composed of four separate parabolic sections 28^a, 28^b, 28^c and 28^d. These four parabolic sections are derived as in the previously described forms from simple parabolic reflectors of such focal lengths that when said sections are assembled and merged together as shown in Figures 17 to 21, their several focal points coincide at the point 29. As in the former cases, the reflector is provided with a lamp socket 30 for receiving a lamp 31, the said lamp and lamp socket being so operatively associated with the reflector that the filament of the lamp is located substantially at the focal point 29 of the reflector.

The reflector unit of Figures 17, et. seq., projects four separate beams of light which are so angularly related that they intersect one another at a point below the focal point 29 of the reflector and in effect spot light each of the four reading zones of the seat grouping D. In this connection, it will be noted that the beams of light projected from the reflector sections 28^a and 28^b intersect one another in a plane extending transversely of the reflector unit along the line 20—20 of Figure 17, while the beams of light projected from the reflector sections 28^c and 28^d intersect one another in a transverse plane extending through the reflector along the line 21—21 of Figure 17. Thus, beams of light projected from the reflector sections 28^a and 28^b are employed to illuminate one pair of diagonally spaced reading zones in the seat grouping D, while the beams of light projected by reflector sections 28^c and 28^d illuminate the other pair of diagonally spaced reading zones in said seat grouping.

Figures 22 to 25, inclusive, illustrate diagrammatically the manner in which the several reflector sections of the multiple reflector 26 are derived and corelated to form the complete reflector unit. Figures 22 and 23 illustrate the formation of the transverse section of the reflector unit as shown in Figure 18, while Figures 24 and 25 illustrate the formation of the transverse section as shown in Figure 19.

The reflector sections 28^a, 28^b, 28^c and 28^d are each derived in similar manner from simple parabolic reflectors *p* of suitable focal length as represented in Figures 22 and 24 which respectively show transverse sections of said reflector taken at right angles to each other. Thus, in plan view the point *a* of Figure 22 is spaced 90° with respect to the point *a'* of Figure 24, and similarly, the points *e* and *e'* are spaced 90° apart. The relative locations of these points *a*, *a'*, *e* and *e'* are shown in Figure 17.

The section 28^a is obtained by cutting a sector from the reflector *p* in such manner that one radially extending edge of the sector lies in that transverse plane of the line *f*—*d* of Figure 22 which extends through the point *a'*, while the other radially extending edge of the sector lies in that transverse plane of the line *f*—*d* extending through the point *a*.

The second section 28^d is similarly obtained by cutting a sector from an identical reflector *p*, but this latter reflector is in this case bounded by a radial edge lying in that transverse plane

of the line *f*—*b* of the Figure 22 which extends through the point *a'*, and by an opposite radial edge lying in that transverse plane of the line *f*—*b* which extends through the point *e*.

5 The third section 28^c is obtained by cutting a sector from a parabolic reflector *p* in such manner that this reflector is bounded on one side by a radial edge lying in that transverse plane of the line *f*—*d'* of Figure 24 which extends through the point *e'*, and on the other side by a radial edge lying in that transverse plane of the line *f*—*d'* which extends through the point *a*.

10 The fourth section 28^b is likewise obtained from a parabolic reflector *p* by cutting therefrom a sector which is bounded on one side by a radial edge lying in that transverse plane of the line *f*—*b'* of Figure 24 which extends through the point *e'*, and on the other side by a radial edge lying in that transverse plane of the line *f*—*b'* extending through the point *e*.

15 The four parabolic sectors so derived from the basic parabolic reflectors *p* are then assembled in relation to each other to provide the form from which is produced the multiple reflector unit shown in Figures 17 to 21, the proximate radial edges of the several parabolic sectors being smoothly merged together and joined along the peak or ridge lines 32, 33, 34 and 35, shown most clearly in Figure 17. In this assembly, it will be observed that each of the reflector sectors have been rotated about a focal point common to them, all in such manner that they project separate beams of light from a common source, the said beams being so angularly related and directed that they intersect one another to respectively illuminate the four reading zones of the seat grouping D.

20 It will be observed that whereas the two halves of the reflector disposed to either side of the line 19—19 of Figure 17 are symmetrical with respect to said line, the two halves of the reflector disposed to either side of the transverse line 18—18 of Figure 17 are not symmetrical. In other words, 25 whereas the vertical plane of the lighting unit taken along the line 19—19 of Figure 17 substantially bisects the angle of divergence of the beams projected from either side of said plane, the beams respectively projected from either side of the transverse vertical plane of the unit taken along the line 18—18 of Figure 17 intersect said latter plane at unequal angles and thus partake of a directional characteristic. More simply stated with reference to the seat grouping D of Figure 1, 30 the beams of light respectively projected from the reflector sections 28^b and 28^c each form angles of 20° forwardly and rearwardly of the focal axis of the reflector and 18° laterally of said axis so as to illuminate the reading zones of the longitudinally spaced aisle seats of the seat grouping D. On the other hand, the beams of light respectively projected from the reflector sections 28^a and 28^d each form angles of 20° forwardly and rearwardly with respect to the focal axis of the unit and only 8° laterally of said axis so as to properly illuminate the reading zones of the longitudinally spaced window seats of said seat grouping D. Of course, this angular relation between the four beams of the reflector unit may be varied as desired depending upon the relative position of the seats to be illuminated and the mounting position of the lighting unit in the vehicle and it is not intended to limit this invention to any particular angular relation of the beams.

35 As has been previously indicated, all of the

multiple reflector units as constructed in accordance with and embodying the principles of the present invention are intended to be mounted in suitable housings therefor, to provide a complete self-contained lighting unit such as is shown and described, for example, in United States Letters Patent No. 2,249,357, hereinbefore referred to. By virtue of the fact that in its preferred form the reflector unit of the present invention is provided with a marginal supporting rim, such reflector may be mounted in the lighting unit of said Patent No. 2,249,357 in the manner and by the means therein described. However, any other suitable arrangement may be employed for housing the multiple-reflector unit of the present invention and it will be understood further that the reflector unit hereof may be modified in different respects, as by changing the number and relative arrangement of the several component reflector sections thereof, without departing from the general principles of the present invention. It is accordingly intended to claim the present invention broadly, as well as specifically, as indicated in the appended claims.

What is claimed as new and useful is:

1. In an interior lighting system for a passenger vehicle having a seat grouping consisting of at least three contiguous passenger seats and corresponding reading zones to be illuminated, a unitary lighting fixture mounted above a seat grouping to be illuminated, said lighting unit being characterized in that it includes a single light source and a relatively shallow multiple-element reflector associated therewith for projecting a plurality of independent intersecting light beams of substantially equal intensity corresponding in number with the number of reading zones to be illuminated, said reflector being composed of a plurality of parabolic sections all of the same focal length and arranged to have separate focal axes intersecting at a common focal point coincident with said light source, the said parabolic sections being all merged to provide a unitary reflector having a smooth reflecting surface and an uninterrupted free marginal edge disposed in a flat plane with the said common focal point of said sections located within the confines of the reflector adjacent the flat plane of the free marginal edge thereof, whereby the several beams projected from the reflector intersect one an-

other at a locus below said common focal point to respectively spot-light simultaneously and with substantially equal intensity the several contiguous reading zones of the seat grouping 5 when said fixture is mounted above said seat grouping.

2. In an interior lighting system for passenger vehicles as defined in claim 1 wherein said seat grouping includes three seats arranged in closely spaced side-by-side relation and said unitary reflector includes three parabolic sections adapted to project directionally controlled light beams, the axes of which intersect below the common focal point of the reflector and lie in a common plane extending at an angle to the vertical whereby, upon mounting said lighting fixture above said seat grouping and somewhat to the rear of the center of the reading zones thereof, the reading zones of the said three seats are respectively illuminated by said light beams passing in front of the eyes of the seat occupants from a point above the backs of their heads.

3. In an interior lighting system for passenger vehicles as defined in claim 1 wherein said seat grouping includes four seats arranged in closely spaced relation and said unitary reflector includes four parabolic sections adapted to project directionally controlled intersecting light beams, the axes of which intersect below the common focal point of the reflector, said parabolic sections being all characterized in that they are each derived from an identical parabolic reflector so cut as to provide each section with a pair of terminal extremities spaced substantially ninety degrees apart in the horizontal plane of the free marginal edge of the reflector and with a third terminal extremity spaced above said plane in such relation to said pair of terminal extremities that lines respectively drawn from said third terminal extremity and from either of said pair of terminal extremities to intersect at the focal point of the parabolic section form an angle greater than ninety degrees, the third terminal extremities of the several reflector sections being smoothly merged together at a point spaced from said common focal point a distance greater than the focal length of any one parabolic section.
